His Attorney.

UNITED STATES PATENT OFFICE.

ASA F. BATCHELDER, OF SCHENECTADY, NEW YORK, ASSIGNEE TO GENERAL ELECTRIC COMPANY, A CORPORATION OF NEW YORK.

LOCOMOTIVE OR CAR TRUCK.

1,277,360

Specification of Letters Patent.

Patented Sept. 3, 1918.

Application filed January 14, 1918. Serial No. 211,759.

To all whom it may concern:

Be it known that I, ASA F. BATCHELDER, a citizen of the United States, residing at Schenectady, in the county of Schenectady, State of New York, have invented certain new and useful Improvements in Locomotive or Car Trucks, of which the following is a specification.

My invention relates to locomotive or car trucks and particularly to trucks for electrically propelled locomotives or cars and has for its object a novel construction by which a very cheap truck can be built.

My invention consists in using the electric motors as part of the mechanical portion of the truck, supporting them between the axles of the truck and a transom, the transom being supported on equalizers, which in turn are supported on the motor frames.

In such a truck, the bearings of the motors on the axles may be used as the main journals, so that no outside journal boxes or equalizers or any frame is required.

Other features of novelty which characterize my invention will be pointed out with particularity in the claims annexed to and forming a part of this specification. For a better understanding of my invention, reference may be had to the following description.

One feature taken in connection with the accompanying drawing, in which Figure 1 is a plan view of a truck embodying my invention; Fig. 2 is an elevation of the truck of Fig. 1 with parts broken away and in section; Fig. 3 is a sectional view taken on the line 3—3 of Fig. 1, and Fig. 4 is a sectional view of the transom.

Referring to the drawing, the axles 1 are provided with the usual wheels 2 and are arranged to be driven by electric motors 3. Each of the motors 3 is supported between one of the axles 1 and a transom 4. Equalizers 5, on which the transom 4 is supported, have supports 6 on the motor frames, these supports being preferably spring supports. These equalizers maintain the proper distance between the axles as will be pointed out hereinafter. Each of the motors 3 is geared to its respective axle through gearing contained within the gear case 7.

Each motor has a nose 8 somewhat similar to the ordinary nose on a railway motor, only larger, which fits into a recess 9 in the transom 4, so as to prevent up and down or

sidewise movement of the motor with respect to the transom. Part of the weight of each motor is thus carried by the transom. The rest of the weight of each motor is carried on the respective axle of the truck, by means of an axle bearing 10 in the frame of its respective motor. This bearing is preferably a single elongated bearing, as shown. The proper distance between the two axles is maintained by the two longitudinal bars 5 which act as equalizers. Lips or projections 11 on the transom fit over the equalizers, whereby the weight of the transom is carried by the equalizers. The ends of the equalizers have lips 12 which fit over spring caps 13. These spring caps surround springs 14 and slide in jaws 15, shown as cast integral with the motor frame, and these parts together form spring supports for the equalizers. This construction prevents longitudinal movement between the equalizers and the spring supports and consequently between the motors and the equalizers. The motors are provided with lugs 16 on both sides of the equalizers 5, and bolts 17 pass through these lugs and slots 18 in the equalizers to form slot and pin connections between the motors and the equalizers.

The outside ends 19 of the transom form a support for the brake rigging, the brake levers 20 being pivotally connected to the ends 19 of the transom and in line with the wheels. The levers 21 for operating the brakes extend upwardly through slots 22 in the ends of the transom. The transom has a cavity 23 in which the usual center plate is mounted. It will thus be seen that all the weight on the center plate together with the weight of the transom and that part of the weight of the motors carried by the transom is hung on the equalizers 5. These equalizers thus form the key to the whole of my truck structure, and by raising the transom sufficiently so that the bars 5 may be removed from under the lips 11, it will be possible to disassemble the whole truck.

Such a truck will be light in weight and inexpensive to build, as it does not require any outside journal boxes, equalizers or outside frames.

I desire it to be understood that my invention is not limited to the particular arrangement shown and described, and I aim

in the appended claims to cover all modifications that do not depart from the spirit and scope of my invention.

What I claim as new and desire to secure by Letters Patent of the United States, is:—

1. A locomotive or car truck comprising wheels, axles therefor, a truck transom, electric motors geared to said axles, each of said axles having a bearing in the frame of its respective motor, each of said motors being also supported on said transom, equalizers, said transom being supported on said equalizers, and supports for said equalizers on said motor frames. 10
2. A locomotive or car truck comprising wheels, axles therefor, a truck transom, electric motors geared to said axles, each of said axles having a bearing in the frame of its respective motor, each of said motors being also supported on said transom, equalizers, said transom being supported on said equalizers, and spring supports for said equalizers on said motor frames. 15
3. A locomotive or car truck comprising wheels, axles therefor, a truck transom, electric motors geared to said axles, each of said axles having a bearing in the frame of its respective motor, each of said motors being also supported on said transom, equalizers, 20 said transom being supported on said equalizers and spring supports for said equalizers on said axle bearings in the motor frames, said equalizers and said spring supports being arranged so as to prevent longitudinal movement between them. 25
4. A locomotive or car truck comprising wheels, axles therefor, a truck transom, an electric motor geared to each of said axles, each of said axles having a single elongated bearing in the frame of its respective motor, each of said motors being also supported on said transom, equalizers, said transom being supported on said equalizers, and spring supports for said equalizers on said 30 axle bearings in the motor frames, said equalizers and said spring supports being arranged so as to prevent longitudinal movement between them. 35
5. A locomotive or car truck comprising wheels, axles therefor, a truck transom, electric motors geared to said axles, each of said axles having a single elongated bearing in the frame of its respective motor, each of said motors being also supported on said transom, equalizers, slot and pin connections between said equalizers and said motor frames, said transom being supported on said equalizers, and spring supports for said equalizers on said axle bearings in the motor frames, said equalizers and said spring supports being arranged so as to prevent longitudinal movement between them. 40
6. A locomotive or car truck comprising wheels, axles therefor, a truck transom, electric motors geared to said axles, each of said 45
7. A locomotive or car truck comprising wheels, a pair of axles therefor, a truck transom, a pair of electric motors, each motor being geared to its respective axle, each of said axles having a bearing in the frame of its respective motor, each of said motors being also supported on said transom, a pair of longitudinally extending equalizers, said transom being supported on said equalizers, and spring supports for said equalizers on said axle bearings in the motor frames, said equalizers and said spring supports being arranged so as to prevent longitudinal movement between them. 50
8. A locomotive or car truck comprising wheels, a pair of axles therefor, a truck transom, a pair of electric motors, each motor being geared to its respective axle, each of said axles having a single elongated bearing in the frame of its respective motor, each of said motors being also supported on said transom, a pair of longitudinally extending equalizers, said transom being supported on said equalizers, and spring supports for said equalizers on said axle bearings in the motor frames, said equalizers and said spring supports being arranged so as to prevent longitudinal movement between them. 55
9. A locomotive or car truck comprising wheels, a pair of axles therefor, a truck transom, a pair of electric motors, each motor being geared to its respective axle, each of said axles having a single elongated bearing in the frame of its respective motor, each of said motors being also supported on said transom, a pair of longitudinally extending equalizers, slot and pin connections between said equalizers and said motor frames, said transom being supported on said equalizers, and spring supports for said equalizers on said axle bearings in the motor frames, said equalizers and said spring supports being arranged so as to prevent longitudinal movement between them. 60
10. A locomotive or car truck comprising wheels, a pair of axles therefor, a truck transom, a pair of electric motors, each motor being geared to its respective axle, each of said axles having a bearing in the frame of its respective motor, each of said motors being also supported on said transom, a pair of longitudinally extending equalizers, slot and pin connections between said equalizers and said motor frames, said transom being supported on said equalizers, and spring supports for said equalizers on said axle bearings in the motor frames, said equalizers and said spring supports being arranged so as to prevent longitudinal movement between them. 65

- son, a pair of longitudinally extending equalizers, said transom being supported on said equalizers, and spring supports comprising spring caps, springs, and jaws on 5 said motor frame, said spring caps sliding in said jaws, said equalizers having lips fitting over said spring caps so as to prevent longitudinal movement between said equalizers and spring supports.
- 10 11. A locomotive or car truck comprising wheels, a pair of axles therefor, a truck transom, a pair of electric motors, each motor being geared to its respective axle, each of said axles having a single elongated 15 bearing in the frame of its respective motor, each of said motors being also supported on said transom, a pair of longitudinally extending equalizers, said transom being supported on said equalizers, and spring supports 20 comprising spring caps, springs, and jaws on said motor frame, said spring caps sliding in said jaws, said equalizers having lips fitting over said spring caps so as to prevent longitudinal movement between said equalizers and said spring supports.
- 25 prevent longitudinal movement between said equalizers and said spring supports. 25
12. A locomotive or car truck comprising wheels, a pair of axles therefor, a truck transom, a pair of electric motors, each motor being geared to its respective axle, each of said axles having a single elongated 30 bearing in the frame of its respective motor, each of said motors being also supported on said transom, a pair of longitudinally extending equalizers, slot and pin connections between said equalizers and said motor 35 frames, said transom being supported on said equalizers, and spring supports comprising spring caps, springs, and jaws on said motor frame, said spring caps sliding in said jaws, said equalizers having lips fitting over said spring caps so as to prevent longitudinal movement between said equalizers and said spring supports. 40

In witness whereof, I have hereunto set my hand this 9th day of January, 1918.

ASA F. BATHELDER.
